UNITED STATES PATENT OFFICE.

ADOLPH I. BLANC, OF DETROIT, MICHIGAN, ASSIGNOR TO PETER P. STONE AND ADOLPH I. BLANC, DOING BUSINESS AS S. & B. SPECIALTIES MANUFACTURING COMPANY, OF DETROIT, MICHIGAN.

RADIOANTENNA.

Application filed March 19, 1926. Serial No. 96,021.

The invention relates to antennae for radio receiving apparatus and is more particularly directed to improvements in aerials of the so called "ball type".

One of the objects of the invention is to provide an improved hollow shell antenna construction adapted to be mounted on a pole or mast and so designed as to effectively insulate the same from grounding under all weather conditions. Another object is to increase the effectiveness of the antenna by the introduction of a coiled conductor within the hollow shell. These and other objects are attained by the novel construction as hereinafter set forth.

In the drawings:

Figure 1 is an elevation of the device.

Figure 2 is a plan view of the insulator coupling.

Figure 3 is an enlarged fragmentary sectional view.

The antenna consists of a hollow metallic shell preferably of substantially spherical form and constructed of a material having good electrical conductivity. In the preferred construction the antenna is built up from two hemispherical sections A and B made from sheet copper and provided with flanges A' and B', which are turned inwardly at C to form a circumferential seam D. The upper section A is entirely closed while the lower section B is slightly flattened at its lowermost portion as indicated at E and provided with an aperture F. A suitable fitting is secured to the shell and arranged to form the support therefor and to be connected to the mast or pole on which the device is to be mounted. The particular fitting which I employ consists of a threaded tube G inserted through the aperture and engaging a nut H, the latter being secured to the inner surface of the shell by soldering or other suitable means. Secured to the threaded tube G is an insulating coupling I which may be of any suitable form adapted to electrically insulate the aerial from the supporting member and at the same time provide the necessary mechanical strength.

As shown in the drawings the coupling consists of two threaded members J and K each of which has radially extending lugs L secured to a disk M of fiber, vulcanized rubber or other suitable insulator. The lugs on the

lower member K are preferably arranged intermediate the lugs on the upper member J to avoid interference of the rivets N, which secure the same to the insulating disk. O is a short section of threaded pipe engaging the member K and P is a standard coupling threaded at T' to receive the pipe Q forming the mast for the antenna.

Secured to the hollow shell and surrounding the insulating coupling I is a protecting shield R, preferably formed of sheet metal as a bell shaped shell. The shield R is secured to the antenna shell by a washer S and lock nut T and forms around the insulating coupling an air chamber U closed at its upper end and open only at the lower end at a considerable distance below the insulating disk M. This construction forms a shield for the insulating coupling which effectively prevents water from reaching the insulator and causing a grounding of the aerial. Since the shield R is preferably made of sheet metal such as brass, it also increases the effectiveness of the aerial as well as providing a protection for the insulation.

The antenna as above described may be made in any size desired, but as a practical device for the reception of broadcasting stations, I preferably construct the antenna as a spherical shell of approximately ten inches diameter. This I have found will be the equivalent of a single strand aerial wire of approximately seventy-five feet in length. In order to increase the effectiveness of the aerial to correspond with a one hundred foot single strand conductor, I have provided within the hollow shell a coiled conductor V having its opposite ends secured to the hollow shell preferably by soldering and being otherwise insulated therefrom. W is a binding post secured to and projecting from the shell preferably at a point spaced slightly from the protecting shield R and provided with a screw cap W' for clamping the aerial lead in wire X. One end of the coil conductor V is usually connected to the binding post W.

With the construction as above described, it will be apparent that I have provided a so called ball type antenna formed as a unit and adapted to be quickly installed in any desired location. The construction is su-

perior to those heretofore employed in the arrangement of the protecting shield for preventing grounding and in the provision of a coiled conductor within the shell for increasing the effectiveness of the antenna.

What I claim as my invention is:

1. A radio antenna comprising a hollow metallic shell, a supporting member therefor, an electrical insulator mechanically connecting said supporting member to said shell, and a metallic protecting shield secured to said shell and entirely surrounding said insulator forming an air chamber closed at the upper end and open at the lower end.
2. A radio antenna comprising a hollow metallic shell, a supporting mast, a fitting secured to and depending from said shell, an insulating coupling connecting said fitting and said mast, and a metallic bell shaped member secured to said hollow shell and surrounding said insulating coupling for protecting said coupling from the weather.
3. A radio antennæ comprising a hollow metallic shell, a tubular fitting secured to and depending from said shell, an insulating coupling secured to said fitting and provided with coupling members adapted for connection to said fitting and to a suitable support, and a protecting shield secured to said

shell and surrounding said insulating coupling.

4. A radio antennæ comprising a hollow metallic shell, a supporting mast, a tubular fitting secured to and depending from said shell, an insulating block, coupling members secured to opposite faces of said block for connecting the fitting and supporting mast respectively, and a metallic bell shaped member secured to said shell and completely surrounding said insulating block and protecting the same from the weather.

5. A radio antenna comprising a hollow metallic shell, a supporting mast, a tubular fitting secured to and depending from said shell, a flat insulating block, a coupling member having a base portion secured to one face of said block and provided with a socket portion for receiving the end of the tubular fitting, a second coupling member secured to the opposite face of the insulating block and connecting the shell and block to the supporting mast, and a metallic protecting shield secured on said fitting between the first mentioned coupling member and the said shell and entirely surrounding the insulating block.

In testimony whereof I affix my signature.

ADOLPH I. BLANC.
